UNITED STATES PATENT OFFICE.

ORLA O. WILCOX, OF DENVER, COLORADO, ASSIGNOR OF ONE-THIRD TO PETER I. VENARD AND ONE-THIRD TO CHARLES W. LOOMIS, BOTH OF DENVER, COLORADO.

CAR-SEAL.

1,169,217.

Specification of Letters Patent. Patented Jan. 25, 1916.

Application filed June 1, 1915. Serial No. 31,527.

To all whom it may concern:

Be it known that I, ORLA O. WILCOX, a citizen of the United States, residing at Denver, in the county of Denver and State 5 of Colorado, have invented certain new and useful Improvements in Car-Seals; and I do declare the following to be a full, clear, and exact description of the invention, such as will enable others skilled in the art to 10 which it appertains to make and use the same.

My invention relates to useful improvements in seals such as those used upon car doors, the object of the invention being to 15 improve upon the general construction of devices of this class to such an extent as to greatly simplify and reduce the cost of manufacture thereof without impairing their efficiency.

With this end in view, the invention resides in certain novel features of construction to be hereinafter fully described and claimed, such features being illustrated in 20 the accompanying drawings which constitute a part of the application and in which:

Figure 1 is a plan view of the blank from which the seal is constructed; Fig. 2 is a similar view of one end thereof showing this end folded upon itself for a purpose to be 25 described; Fig. 3 is a perspective view of one form of seal constructed from the blank shown in Figs. 1 and 2; Fig. 4 is a longitudinal sectional view of such form previously to inserting the free end of the seal 30 for engagement by the fastener; Fig. 5 is a similar view after inserting such end of the seal; Fig. 6 is a horizontal section as seen on the plane indicated by the line 6—6 of Fig. 5; Fig. 7 is a side elevation of an additional form of the invention; and, Fig. 8 is 35 a top plan view of such form.

In describing the invention, I shall refer to these drawings by similar reference characters placed on corresponding parts 40 throughout the several views, the numeral 1 having reference to a flat strip of pliable metal having in one end an opening 2, while its other end is given one bend rearwardly upon itself as seen at 3 whereby to provide 45 two thicknesses of metal, the last mentioned end being disposed in a plane parallel to the strip 1 and spaced therefrom for a purpose to be described. The aforesaid two

thicknesses of metal are provided with alined slots 4 which may be of the shape 55 shown in the drawings or of any other preferred form.

Passing through the aline slots 4 is the bend of a substantially U-shaped fastener 5 which is disposed in a plane at right angles 60 to the strip 1 and having its free ends bent inwardly toward each other to provide locking bolts 6 which, when not held spaced apart will assume the relative positions shown in Fig. 5, such bolts, however, being 65 normally spaced from each other by disposing their inner adjacent ends in contact with the opposite sides of the folded end of the strips as clearly shown in Fig. 4, whereupon the end of said strip having the opening 2 may be readily inserted between the 70 two thicknesses of metal above described, such end being then forced into contact with the bend of the fastener 5, whereby the latter is shifted within the slots 4. This movement brings the two bolts 6 opposite the adjacent ends of said slots and allows said bolts to spring therethrough. By the time this movement takes place, the opening 2 is so disposed as to allow the bolts to be projected therethrough in addition to being extended through the slots 4, thereby effectively anchoring the free end of the seal. 75

In order to prevent tampering with the fastener 5, a casing necessarily surrounds 80 the folded end of the strip 1 and the edges of said fastener which project laterally from said folded end. As a simple and unique manner of forming such casing, a rectangular wing 7 is formed integrally with one 85 edge of the last named end of the strip 1 opposite the two thicknesses of metal as clearly shown in Figs. 1 and 2, such wing being carried completely around this end of the strip and the projecting edges of the fastener 90 and having its free end anchored either by riveting as shown in Figs. 3 and 6, or by merely crimping as disclosed in Figs. 7 and 8. In either case, the portions of the wing between the edges of the strip and the 95 edges of the fastener 5 are bent inwardly to form right angular walls 8 which substantially contact with the opposite sides of said fastener and those of said strip. By so constructing the casing, the fastener 5 is held 100 in its proper relation to the other parts of

the device and is allowed the necessary sliding movement, in addition to being protected against molestation.

From the foregoing description, taken in connection with the accompanying drawings, it will be evident that although extremely simple construction has been provided, the entire device being constructed only of one sheet of metal and one piece of resilient wire, the result of such construction is an article which may be inexpensively manufactured and marketed and which will be efficient and durable when applied to use.

I claim:

15 A seal comprising a flat strip of metal having one end thereof bent backwardly upon itself to provide two thicknesses of metal, said end being disposed in a plane parallel to said strip and spaced therefrom, 20 said two thicknesses of metal having alined slots therethrough, the other end of said strip being provided with an aperture, a U-shaped spring slidable in said slots and disposed in a plane at right angles to said strip,

the free ends of the former being turned inwardly toward each other and projected through said slots and the opening in the last mentioned end of said strip upon the insertion of said end between the two thicknesses of metal, a rectangular wing extending laterally from one side of said strip opposite the two thicknesses of metal, said wing being carried transversely around the latter and said spring, the portions of the wing between the edges of the strip and the edges of the spring being bent inwardly to provide right angular walls disposed substantially in contact with the sides of said strip and the sides of said fastener, and means for anchoring the free ends of said wing, substantially as described.

In testimony whereof I have hereunto set my hand in presence of two subscribing witnesses.

ORLA O. WILCOX.
